UNITED STATES PATENT OFFICE.

ALBERT EDWARD RUSSELL, OF WELLINGTON, NEW ZEALAND.

DESIGN FOR A STATUETTE.

Application filed May 12, 1924. Serial No. 9,566. Term of patent 7 years.

To all whom it may concern:

Be it known that I, ALBERT EDWARD RUSSELL, a subject of the King of Great Britain, residing at Wellington, in the Dominion of New Zealand, have invented a new, original Design for a Statuette, of which the following is the specification, reference being had to the accompanying drawings, forming part thereof.

I claim:

The ornamental design for a statuette, as shown.

In testimony whereof I affix my signature.

ALBERT EDWARD RUSSELL.

Witnesses:

ROBERT MARTIN FARQUHAR,
ENGR. WEMKLYM MARCEAU.
